PIPE CLEANING APPARATUS

Roy T. Quick, Los Angeles, Calif., assignor to
George H. Werfelman, Los Angeles, Calif.

Application July 31, 1937, Serial No. 156,686

8 Claims. (Cl. 242—54)

My invention relates broadly to apparatus for cleaning pipes of all kinds, and particularly to the cleaning of sewers, drain pipes and the like, which have become stopped up or clogged with solid matter.

It is the major object of my invention to provide a simple and durable apparatus for cleaning pipes which is extremely efficient and capable of operating successfully on all kinds of stoppages in all kinds of pipe.

The apparatus of my invention is generally of the type shown in the U. S. patent to Magruder, No. 2,075,215, and is particularly directed to providing an improved reel and wire-holding apparatus in the revolving carriage type of machine shown in that patent.

A preferred form of my apparatus is illustrated in the attached drawings, in which:

Fig. 1 is a perspective of the complete apparatus,

Fig. 2 is a plan view of the same,

Fig. 3 is a side elevation partly in section of the main working parts thereof,

Fig. 4 is a fragmentary section taken at line 25 4—4 of Fig. 3,

Fig. 5 is fragmentary section taken at 5—5 in Fig. 4, and

Fig. 6 is a detail section of a guide roller assembly taken at 6—6 in Fig. 3.

Referring now to the drawings and particularly to Fig. 1 thereof, the numeral 10 indicates generally a main frame which if desired may be provided with wheels 11. The frame 10 may be of any suitable construction but I prefer that it shall comprise a bed or base plate 13, uprights or posts 14, longitudinal horizontal members 15, and cross-members or end plates 16 and 16a. An additional supporting member or cross-bar 12 extends across the frame adjacent the end plate 16 and is provided with a bearing 17, a corresponding bearing 17a being provided in end plate 16a.

A reel carriage indicated generally by the numeral 19, preferably comprising a pair of head plates 20 and 20a and four longitudinally-extending rods 21 secured between the head plates is revolvably mounted in the frame 10 by means of a pair of trunnions 18 and 18a extending from head plates 20 and 20a respectively and 50 journalled in the bearings 17 and 17a. A wire-holding reel 22 is rotatably mounted within the carriage 19 in any convenient manner, such as shaft 23 extending between a pair of side plates or brackets 24 and 24a, fastened between vertically opposed pairs of the longitudinal rods 21.

By this construction the carriage 19 is adapted to revolve about the axis of trunnions 18 in frame 10, and reel 22 is adapted to rotate about its normal axis 23 in carriage 19.

A coil of wire 25 is wound on the reel 22 and its free end 25a is led outside of the carriage 19 and frame 10 in any convenient manner but preferably on the axis of trunnions 18 and 18a. This is most easily accomplished by making one of the trunnions hollow or tubular and in the form 10 shown in the drawings, trunnion 18 is so constructed. A pipe cleaning tool of any suitable type is fastened on the free end 25a of the wire, and it will be seen that rotation of the reel 22 in its carriage 19 will advance or retract the wire 15 and tool, while revolution of the carriage 19 and reel 22 about the trunnion axis of the carriage will cause the wire and tool to rotate about their longitudinal axis.

In the ordinary operation of my device, it is 20 highly desirable that the revolution of the carriage 19 and the rotation of the reel 22 be independently controlled so that these movements may be had simultaneously or separately and at independently variable speeds. Any suitable means 25 for accomplishing this result may be employed, one very simple and efficient means being illustrated in the drawings as seen best from an inspection of Figs. 2 and 3. In this form of my device, the trunnion 18 is provided with a pulley 30 26 adapted to be driven by a belt 30 connected to any suitable source of power such as a motor 31 mounted on the bed plate 13. Any suitable means (not shown) may be employed for varying and controlling the speed of pulley 26 and hence 35 trunnion 18 and carriage 19.

To rotate the reel 22, a hollow shaft 33 may be rotatably mounted in tubular trunnion 18 and extend through and beyond each end thereof. On the outer end of shaft 33, I provide suitable 40 driving means such as a variable radius pulley 32 which is normally held at its maximum diameter by suitable spring means 34 adapted to bear on the shoulder 35 of the pulley and also on nut 29 on the outer end of the shaft 33. A gear 45 36 is keyed on the inner end of shaft 33 just inside of carriage head plate 20 and engages a gear 37 carried by a horizontal shaft 38 suitably journalled in the carriage 19. The other end of shaft 38 carries a beveled pinion 39 adapted to 50 mesh with a beveled ring gear 40 fastened to the reel 22. It will thus be seen that rotation of pulley 32, as for instance, by a belt 51, rotates hollow shaft 33 and gear 36, which drives gear 37 and shaft 38 to rotate beveled gears 39 and 55

40 and thus rotate reel 22 on its normal axis 23. The pulley 32 may be driven by any suitable means such as a drive pulley (not shown) on the shaft of motor 31, or may be driven independently, the principal requirement being that its speed be variable with respect to the speed of pulley 26 and trunnion 18. While I have shown and described the shaft 33 as being hollow to accommodate the wire 25, it will of course be understood that trunnion 18a may be made tubular to provide an axial passage for the wire, and in that case shaft 33 is preferably made solid.

As will be obvious to those skilled in the art, high speed rotation of the reel 22 tends to throw the wire 25 outwardly from the reel rim, and it will be found whenever the pipe cleaning tool is working on an obstruction that the wire 25 will tend to rise off of the reel 22. It thus becomes imperative to provide adequate means for holding the wire 25 tightly on the reel 22 at all times, and to also provide a simple and efficient means for winding and unwinding the wire at will, both when the carriage 19 is at rest and when it is revolving.

Referring now particularly to Figs. 4 and 5 it will be seen that the reel 22 comprises a hub 41, spokes 42 and a rim 43 adapted to receive the wire 25. My preferred means for holding the wire on the reel at all times is as follows. Brackets 45 and 45a, preferably circular in shape are mounted on each side of the reel carriage 19 by any suitable means, and with their center on the axis 23 of the reel 22. A plurality of outwardly-extending radial guide members 50 and 50a are secured to the brackets 45 and 45a respectively, the guides being arranged in pairs so that a guide 50 is always opposite to a guide 50a on the other side of the reel 22. The guides are preferably provided with radial slots 51 as seen best in Fig. 5 and rollers 52 are mounted in the opposed slots of oppositely disposed guides 50. Suitable spring means such as the helical springs 53 and 53a are respectively connected between the outer ends of the roller shafts 54 and the circular brackets 45 and 45a, to continually pull the rollers 52 inwardly and radially toward the reel rim 43. As will be seen, the slots 51 are so proportioned that the rollers 52 will at all times bear against the wire 25 on rim 43, regardless of how much or little wire may be on the reel at the moment, and by forming the springs 53 of suitable size and strength a very considerable pressure can be applied to the wire 25 by means of rollers 52.

The rim 43 may be formed with annular sides if desired to hold the wire 25 against lateral movement on the rim, it being only necessary to shorten the rollers 52 so that they can move down inside of the rim sides and to complement the axle shaft 54 with a pair of radial lugs or brackets with laterally-extending portions adapted to ride in the slots 51 and be secured by spring means 53. However, I prefer to have the reel rim 43 flat and to so space the guides 50 and 50a that a substantially sliding fit is had between the rim 43 and the guides 50 and 50a, thus preventing the wire 25 from slipping off the rim, even when a considerable amount has been wound thereon. If, as is the case under some conditions, it is necessary to cut down the friction drag between the guides 50 and the rim 43 and wire 25, I provide a series of radial guide rollers 60, preferably mounted on laterally extending ears carried by the guides 50 as seen best in Fig. 5. In this case the rim 43 preferably does not

touch the guides 50 but does engage the plurality of radial rollers 60, so that the wire 25 is at all times held against lateral movement away from the rim.

It will be understood of course that the 5 brackets or frames 45 45a and the guides 50 50a may be formed as solid housings with suitably disposed bearings for the spring-pressed rollers 52 and the guide rollers 60 if they be used. However, the form of my invention illustrated herein 10 is deemed to be the most economical of construction, efficient in operation, and accessible for repairs or adjustments.

Referring now particularly to Fig. 2, the numeral 62 indicates a transverse brace extending 15 between a pair of opposed longitudinal arms 21 adjacent the end of the carriage from which the wire 25 is to be led. An angularly positioned plate 63 is mounted on the brace 62 and extends toward the reel 22 on a line substantially tangential to its surface at the point on the reel where the wire 25 is to leave the same. The plate 63 is provided with a plurality of guide rollers 64 preferably having grooved or concave circumferential faces to accommodate and guide 25 the wire 25 from the reel 22 to the hollow shaft 33. To adjust the angular position of the roller plate 63 and to reinforce it, I provide an angularly extending bracket 65 which also may be mounted on the cross-brace 62 and parallels the 30 plate 63. The outer or free ends of the plate 63 and bracket 65 are preferably joined by a bolt 66 provided with a lock nut 67 to permit the space between the bracket and the plate to be varied. The plate 63 may be made semi-flexible or may 35 be pivotally mounted so as to facilitate adjustment. Likewise, it can be curved to conform to the natural path of the wire 25 if desired.

The operation of my preferred form of apparatus illustrated herein, is as follows: 40

A cleaning tool of suitable form is fastened to the free end of the wire 25 extending beyond the machine, the power source is energized, and by reason of belts 30 and 57 the pulleys 26 and 32 are caused to rotate. The pulley 26 keyed to 45 trunnion 18 causes the reel carriage 19 to revolve, and the pulley 32 causes rotation of shaft 33 and gear 36 about the axis of trunnion 18. As long as the speeds of rotation of the two pulleys 26 and 32 are the same, there will be no relative 50 motion of the gear 36 with respect to either the trunnion 18 or the gear 37 carried by shaft 33 in the reel carriage 19. If it is desired to pay out the wire and feed it into a pipe to be cleaned, the speed of the pulley 32 is increased by placing 55 increased tension on the belt 57 by any convenient means such as an idler pulley 68 which causes the adjustable sheave to spread out against the force of spring 34 thus reducing the diameter of the pulley 32 and decreasing the 60 ratio between it and the driving pulley on the motor shaft. This increase in speed of pulley 32 and its attached gear 36 causes the gear 37 to rotate, which in turn causes the reel 22 to rotate about its normal axis 23 to pay out the wire 25 65 which passes under guide rollers 64 and through hollow shaft 33 to the pipe being cleaned. Alternative means for placing tension on the belt is to provide a variable sheave pulley on the drive shaft also and to vary its diameter manually to 70 vary the belt tension and hence the speed of pulley 32.

When it is desired to withdraw the wire 25 from the pipe being cleaned and rewind it on reel 22, the speed of pulley 32 is decreased below 75

the speed of the trunnion pulley 26 and relative motion of gear 37 is effected in an opposite direction, causing the reel 22 to again rotate on its axis 23 but in a reverse direction.

5 If it is also desired to vary the speed of the carriage 19, this can be done in several convenient ways such for example, as providing a rheostat on the motor to control its speed, by using a variable sheave pulley at 26 with an idler pulley such as 53, or by other suitable means. Likewise, 10 if it is desired to rotate the reel 22 to feed the wire 25 without rotating the carriage and wire, suitable clutch means may be provided for entirely disconnecting pulley 26 from trunnion 18 at will, or separate power sources may be used.

15 As will be evident from the foregoing, no matter what type of driving means is used in my apparatus, relative high speeds are desirable and consequently it is essential to provide adequate means for firmly holding the wire 25 on the reel at all times and still allowing it to be wound or unwound thereon at high speeds. By mounting the series of spring-pressed rollers 52 on the carriage, I do away with the necessity of moving parts 20 which have to open and close once during each rotation of the reel and by so doing I achieve a simplicity of construction and longer life for my apparatus. Furthermore, the wire 25 is positively held on the rim at all times irrespective of how 25 full the reel is or how fast it is moving.

30 It will be evident, of course, that the wire-holding means herein described can be used in connection with a reel mounted in a stationary carriage as for instance the type used in pushing wires or cables through conduits where it is not necessary to rotate the wire on its longitudinal axis.

35 While the embodiment of my invention shown herein is fully capable of attaining the objects and providing the advantages stated, it is to be understood that it is merely illustrative of the true scope of my invention as defined by the appended claims.

40 I claim as my invention:

45 1. In pipe cleaning apparatus the combination of: a frame; a carriage revolvably mounted in said frame; a wire receiving reel rotatably mounted in said carriage with its axis of rotation substantially at right angles to that of said carriage; a plurality of transverse rollers mounted on said carriage adapted to press said wire on the rim of said reel; a plurality of radial rollers also mounted on said carriage adapted to hold said wire from lateral movement; and means for revolving

50 said carriage and independently rotating said reel therein.

2. Apparatus as defined in claim 1 in which the carriage is provided with a series of rollers for guiding said wire from said reel out of said carriage and frame. 5

3. Apparatus as defined in claim 1 in which the carriage carries an angularly-disposed plate provided with rollers for guiding said wire from said reel and out of said carriage. 10

4. In pipe cleaning apparatus the combination of: a main frame; a carriage revolvably mounted in said frame by means provided with a tubular passage; a reel with a coil of wire thereon rotatably mounted in said carriage with its axis of rotation substantially at right angles to that of said carriage; means for revolving said carriage and rotating said reel therein irrespective of the revolution of said carriage; a pair of brackets, one on each side of said carriage; a plurality of outwardly-extending radial guides mounted on each of said brackets the guides on said brackets being arranged opposite one another; a roller mounted in each of said pairs of opposed guides, said rollers being adjacent the rim of said reel; and spring means on said carriage for urging said rollers into contact with said coil of wire. 15 20 25

5. Apparatus as defined in claim 4 in which a plate carrying rollers adapted to guide said wire from said reel to said tubular passage is mounted on said carriage. 30

6. Apparatus as defined in claim 4 in which said radial guides are provided with radial rollers adapted to prevent said coil of wire from moving laterally off of said reel. 35

7. In pipe cleaning apparatus the combination of: a frame; a carriage revolvably mounted in said frame; a wire receiving reel rotatably mounted in said carriage with its axis of rotation substantially at right angles to that of said carriage; means for independently revolving said carriage and rotating said reel therein; guide means on each side of said carriage adjacent the rim of said reel providing a plurality of opposed radial slots; a transverse roller mounted in each pair of slots adjacent the rim of said reel; and spring means on said carriage for urging said rollers into contact with wire on said rim to hold the same firmly in position thereon. 40 45

8. Apparatus as defined in claim 7 in which said guide means is provided with a plurality of radial rollers adapted to hold said wire from lateral movement. 50

ROY T. QUICK.
